COMBINED ASH TRAY AND COASTER

Samuel R. Larzelere, Laurel Springs, N. J.

Application May 9, 1942, Serial No. 442,362

3 Claims. (Cl. 131—238)

My invention relates to improvements in combined ash trays and coasters for use as a table accessory, the principal object in view being to provide a device of this character for obviating in the use thereof tablecloth burns and stains, and the like, and which may be distributed to the trade in the form of an inexpensive prepared blank easily folded by a housewife, for instance, to form the ash tray and coaster.

Other and subordinate objects are also comprehended by my invention, all of which, together with the precise nature of my improvements will be readily understood when the succeeding description and claims are read with reference to the drawings accompanying and forming part of this specification.

In said drawings:

Figure 1 is a view in top plan of my combined ash tray and coaster in its preferred embodiment,

Figure 2 is a view in end elevation,

Figure 3 is a view in side elevation,

Figure 4 is a view in transverse section taken on the line 4—4 of Figure 1,

Figure 5 is a view in longitudinal section taken on the line 5—5 of Figure 1,

Figure 6 is a view in transverse section taken on the line 6—6 of Figure 1.

Figure 7 is a view in transverse section taken on the line 7—7 of Figure 1 and drawn to a greatly enlarged scale, and

Figure 8 is a plan view of the blank from which the ash tray and coaster are formed.

Referring to the drawings by numerals, and first to Figure 8 illustrating the prepared blank, said blank comprises a body portion having the form of a partially circular flap 16 provided with radial ribs 17, and a rectangular panel 12 lying in the same plane as the flap 16 and extending lengthwise tangentially from the flap 16 which extends from one side of said panel 12 adjacent one end thereof. A short, rectangular strip-like side flap 2 extends along said side of the panel 12 for bending upwardly thereof along a longitudinal line *d*, one end of said flap 2 extending beyond the corresponding end of the panel 12. A side flap 3 extends along the other side of the panel 12 and beyond said panel in a manner similar to flap 2 and for bending on a longitudinal line *f*. Adjacent one end of flap 3 a short slit *g* is formed between the same and the panel 12. An end flap 1 extends from the end of panel 12 for folding along a transverse line *i*, a shorter strip-like flap 5 extends from the other end of said panel 12 for bending along

5 a transverse line *k*, and a relatively longer flap 6 extends from flap 5 for folding along a transverse line *m*. From one end of flap 3 a relatively shorter similar flap 7 extends endwise for folding on flap 3 along a transverse line *o*, and from the opposite end of the flap 7 a similar longer flap 8 extends endwise for folding thereon on a transverse line *q*. A panel of elongated rectangular form extends endwise from one side edge of flap 8 with a central narrower tab 13 extending from its opposite end. The panel is divided into a pair of flaps 9, 11 and an intermediate flap 10, the end flap 1 being foldable on the flap *p* on a transverse line *w* and the flap 11 on the flap 9 on a transverse line *x*, the flap 11 being foldable on the flap 10 on a transverse line *y*, and the tab 13 being foldable on the flap 11 on a transverse line *z*. The flap 10 is cut out to provide a pair of arcuate edge tabs 14, 15 on the flaps 9, 11, respectively, in the transverse center thereof. At the other end of the flap 3 is a flap 4 similar to flap 7 foldable on a line *w'*, and a shorter flap 2' foldable on flap 4 on a transverse line *y'*.

20 The described blank is folded in a manner now to be described to provide an elongated rectangular ash tray with a coaster extending from one side thereof. First, flap 1 is folded up on line *i* on the panel 12 to form an end wall 1 at one end of the ash tray extending above the sides thereof. The flap 2 may then be folded up on line *d* to form part of an inner side wall 2 on one side of the ash tray. Next, flap 3 is folded up on line *f* to form the other side wall 3 of said tray, flap 4 folded on line *w'* to form an inner end wall 4 at the other end of said tray, and flap 2' folded on line *y'* to align with flap 2 and complete the side wall 2. The flap 5 is folded on line *k* against flap 4 to form an outer end wall 5 against end wall 4 at the corresponding end of the tray, and flap 6 folded on line *m* over the upper edge of flap 10 and over panel 12 to form an inner top wall 6 closing approximately one-half of the top of said tray. Next, flap 7 is folded on line *o* across end wall 1 outside the same to form a keeper wall 7, and flap 8 then folded on line *q* alongside the side wall 2 to form an outer side wall 8 along the same. As will be noted, since the flaps 3 and 2 extend beyond one end of the panel 12, as previously described, the keeper wall 7 is spaced from the end wall 1. Next, flap 9 is folded outwardly on line *w* up along side wall 8, as at 9, flap 10 folded on line *x* over top wall 6 to form an outer top keeper wall 10 overlying wall 6, flap 11 folded down on

line *y* alongside side wall 3, and tab 13 folded on line *z* and tucked through slit *g* into the bottom of said tray over the panel 12 forming the tray bottom and whereby said tab 13 forms a locking device through the medium of which all of the described flaps are held in folded position. The tabs 14, 15 when the flaps 9 and 11 are folded assume upright positions on opposite sides of the ash tray forming finger grips 14, 15. The space between the keeper wall 7 and end wall 8 may be used for inserting a match book, not shown, therein. The flap 16 forms the coaster, as will be clear, with radial ribs 17 thereon.

As will now be seen, the ash tray and coaster are formed of one piece of material, preferably cardboard, the coaster 16 extends from one side of said tray adjacent one end for convenient use thereof, and said end of the tray is covered for use, if desired, in laying a cigar butt thereon between the hand grips 14, 15, while the other end of said tray is open and offset from the coaster 16 within convenient, easy reach without interference with a glass set on the coaster 16. The match book, not shown, is held in a convenient position for access thereto when desired. Also, the sides and ends of the ash tray are reinforced. The folding lines described are preferably impressed in the described blank. The ribs 17 tend to prevent a glass on the coaster from slipping and from adhering thereto.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. An ash tray comprising a single piece of foldable material, said tray including an elongated rectangular bottom, side walls folded upwardly from the sides of the bottom and having ends extending beyond one end of said bottom, an inner end wall folded up from said end of the bottom and extending above the side walls, an outer end wall of the same height as the side walls folded on the extending end of one side wall and extending across the inner end wall against the extending end of the other side wall whereby said end walls are spaced apart to accommodate a match book therebetween, a supplemental side wall folded on the outer end wall and extending alongside said other side wall, and means to maintain the side walls and said outer end wall upright against unfolding and comprising a flap unit of a width corresponding to substantially one-half of the length of said bottom

and side walls folded upwardly alongside the supplemental side wall and across the upper edges of said side walls and down along said one side wall and including an end flap interlocked with said one side wall, an intermediate flap of said unit forming a bridging member extending across substantially one-half of the top of the tray for holding cigarettes thereon and whereby the other half of the tray is open to receive cigarette ashes and butts.

2. An ash tray comprising a single piece of foldable material, said tray including an elongated rectangular bottom, side walls folded upwardly from the side of the bottom and having ends extending beyond one end of said bottom, an inner end wall folded up from said end of the bottom and extending above the side walls, an outer end wall of the same height as the side walls folded on the extending end of one side wall and extending across the inner end wall and against the extending end of the other side wall whereby said end walls are spaced apart to accommodate a match book therebetween, a supplemental side wall folded on the outer end wall and extending alongside said other side wall, and means to maintain the side walls and said outer end wall upright against unfolding and comprising a flap unit of a width corresponding to substantially one-half of the length of said bottom and side walls folded upwardly alongside the supplemental side wall and across the upper edges of said side walls, and down along said one side wall and including an end flap interlocked with said one side wall, an intermediate flap of said unit forming a bridging member extending across substantially one-half of the top of the tray for holding cigarettes thereon and whereby the other half of the tray is open to receive cigarette ashes and butts.

3. A blank of foldable material for forming a cigarette tray, comprising an elongated rectangular section for forming the bottom of the tray, a series of elongated rectangular flaps extending along one side and beyond the ends of said section and foldable upon one another to form side and end walls, a rectangular elongated flap unit extending endwise from one of the side walls forming flaps of said series and including an intermediate flap for bridging the side walls, and flaps adjacent the intermediate flap for folding alongside said side walls, said flap unit including a reduced end flap, and one of the side wall forming flaps being slotted for the insertion of the reduced flap therein to anchor the flap unit in place when folded.

SAMUEL R. LARZELERE.
